UNITED STATES PATENT OFFICE.

ROBERT Y. BARROWS, OF RUTHERFORD, NEW JERSEY.

DESIGN FOR A BOWL FOR LIGHTING-FIXTURES.

57,301.

Specification for Design.

Patented Mar. 15, 1921.

Application filed August 16, 1919. Serial No. 318,046. Term of patent 14 years.

To all whom it may concern:

Be it known that I, ROBERT Y. BARROWS, a citizen of the United States, residing at Rutherford, in the county of Bergen and State of New Jersey, have invented a new, original, and ornamental Design for a Bowl for Lighting-Fixtures, of which the following is a specification, reference being had to the accompanying drawing, forming part thereof.

Figure 1 is a side view of a bowl for lighting fixtures showing my new design. Fig. 2 is a sectional view of the same. Fig. 3 is a bottom plan view thereof.

I claim:

The ornamental design for a bowl for lighting fixtures, as shown.

ROBERT Y. BARROWS.
